UNITED STATES PATENT OFFICE.

ROBERT J. MAGOR, OF MONTREAL, QUEBEC, CANADA, ASSIGNOR TO MAGOR CAR CORPORATION, OF NEW YORK, N. Y., A CORPORATION OF DELAWARE.

CORNER POST FOR FREIGHT CARS.

Application filed July 31, 1926. Serial No. 126,206.

The invention relates in general to an improvement in the construction of the corner posts and of the associated ends in a freight car and the invention specifically 5 relates to an improved form of pressed plate corner posts and associated end boards.

It is a usual practice in constructing freight and like industrial cars to bolt the ends, which are sometimes made of wooden 10 boards, directly to the corner posts but this manner of attaching the ends necessitates the providing of bolt holes in the sheet of metal of which the posts are usually formed with a resulting tendency to weaken the 15 corner posts. From an economic standpoint, it is inadvisable to make these corner posts of any heavier metal.

The primary object of the invention is to provide a simplified and rugged form of 20 corner post and incidentally to provide means for attaching the ends to the corner posts without necessity of weakening the posts by bolt holes, and on the contrary to provide a form of attachment which will 25 tend to reinforce the corner posts in the direction in which it has been weakened heretofore, that is, transversely of its web portion.

Broadly, this phase of the invention is 30 attained simply by securing an angle or other form of initial shape and of any necessary dimension to the rear face of the corner post and to secure the end or the boards forming the end to the angle rather 35 than to the corner post itself.

Incidental to this construction, the invention features the arrangement of the ends flush with the outside of the corner post, which arrangement protects the ends of 40 the boards when used to form the car ends, gives a better appearance to the car end as a whole, provides for greater loading space with no greater overall length of the car and permits the use of boards shorter 45 than have been used heretofore.

Still another object of the invention is to provide an end structure to the car which will permit a limited flexing of the end relative to the car as a whole and at the same 50 time provide a well braced end structure capable of meeting standardized requirements.

In addition to bracing the corner posts transversely, the invention has for another 55 object the locating of a supplemental reinforcement along the line of the floor of the

car where occurs the maximum stress due to the lading in the car, and at the same time minimizes the amount of material used for this purpose.

This phase of the invention is attained 60 by positioning a corner clip at the bottom of the angled reinforcement as it meets the top of the end sill or other transverse member at the floor line.

Various other objects and advantages of 65 the invention will be in part obvious from an inspection of the accompanying drawings and in part will be more fully set forth in the following particular description of one form of mechanism embodying the invention, and the invention also consists in 70 certain new and novel features of construction and combination of parts hereinafter set forth and claimed.

In the accompanying drawings: 75

Fig. 1 is a view in side elevation of a corner post and adjacent parts illustrating a preferred embodiment of the invention;

Fig. 2 is a view in elevation of the part of 80 the car end looking at the frame from the right hand side of the showing in Fig. 1; and

Fig. 3 is an enlarged transverse sectional view taken on the line 3-3 of Fig. 1.

In the drawings there is shown a pressed 85 plate corner post 10 provided with outstanding flanges 11 and 12 and otherwise responding to conventional structure except that the flange 11 is not perforated with bolt holes or other fastening means for securing the 90 end boards.

An angle 13 has one of its flanges 14 secured by means of rivets 15 to the rear side of the web 16 and the corner post 10. The inwardly projecting flange 17 of the 95 angle is spaced from the inner edge of the corner post formed by the flange 11, a distance equal, approximately, to the width of the end board 18. From this construction it will be understood that the outer face of 100 the flange 17 coacts with the portion of the corner post projecting beyond the same to form a rectangular seat for receiving the end edges 19 of the end boards 18. The end boards are secured in place by bolts 20 105 passed therethrough and through the flange 17. From this construction it will be understood that the end boards 18 are not directly secured to the corner posts but are secured 110 to the angle iron which also constitutes a

reinforcement for the corner posts and braces the same in a direction transversely of the corner post. A corner clip 21 is secured by means of two bolts 22 to the lower edge of the flange 17 and includes a portion 23 which rests on and may be secured to the top of the end sill or other transverse member 24 forming the structural part of the car underframe.

10 By means of the construction disclosed it is possible without material additional expense to brace the conventional corner post laterally of the car and incidentally minimize the weakening effect due to the presence of the bolt holes heretofore regarded as necessary to secure the end boards in place. Fitting the end boards between the corner posts provides for a neater appearance, protects the ends of the boards, increases the loading space and provides a car end of materially stronger construction. The end boards are not as easily ripped from the angle iron as they could be torn from thinner material forming the plate corner posts and there is accordingly a resulting saving in replacement costs.

While the car end thus formed is of sufficient ruggedness to meet the car builders' standardized requirements there is provided a limited flexure to the end as a whole and to the end in its relating to the balance of the car so that strains thereon are readily absorbed and transmitted without tendency to rupture the structure.

35 Having thus described the invention, I claim:

1. In a car, the combination of a flanged pressed plate corner post, an angle having one flange secured to the web portion thereof and extending lengthwise and vertically of the same, a vertically disposed end board extending transversely of the car and having an end thereof fitted in the seat between the post and the angle and bolts passed through the other flange of the angle and the end board adjacent the end thereof engaging the corner post.

2. In a car, the combination of a flanged pressed plate corner post, an angle secured to the web portion in spaced relation to one of the flanges and coacting to form a seat for receiving an end of an end board, one

of the angle flanges being provided with bolt holes for receiving the bolts used to secure the end board to the corner post.

3. A car end including at one side a pressed plate corner post including a flange, an end board flush with said flange, an angle fitted between the post and end board and means for securing the end board to the angle.

4. In a car, the combination of a corner post, an angle secured thereto to brace the same transversely and an end board secured to the angle and free of direct fastening connections with the corner post.

5. In a car end, the combination of a corner post, an end abutting edgewise against the inner side of the post and all of said post positioned exteriorly of said end and means including an angle iron fitted in the angle between the corner post and the end for securing the end in its abutting relation to the corner post.

6. In a car end, the combination of one piece channel shaped corner post with its inner face flat and provided with outwardly extending flanges, a vertically disposed transverse board abutting at one end against said flat face of the corner post and fastening means between one side of the board and said flat face for securing the post and board.

7. In a railway car, the combination of a metallic corner post, an end abutting the post and extending inwardly of the post and transversely of the car and means engaging the inner side of the post for reinforcing the same and for providing a connection between the end and the post.

8. In a freight car, the combination of a transverse member, a pressed plate corner post, a bracing for the corner post and a corner clip positioned between the corner post and the transverse member.

9. In a freight car, the combination of a pressed plate corner post, a transverse member, an angle secured to the part of the corner post above the transverse member and a corner clip fitted in the corner formed by the post, transverse member and angle.

Signed at New York, in the county of New York and State of New York, this first day of June, A. D. 1926.

ROBERT J. MAGOR.
